(57) **CLAIM**

The ornamental design for a tire, as shown and described.

DESCRIPTION

FIG. 1 is a perspective view of a tire showing my new design, it being understood that the tread is repeated throughout the circumferential length of the tire.

FIG. 2 is a front elevation view of the tire of FIG. 1, the opposite rear elevation view having an appearance that is a mirror image of the front elevation view.

FIG. 3 is a right-side elevation view of the tire of FIG. 1; and,

FIG. 4 is a partial enlarged view of the tread of the tire of FIG. 1.

The dashed lines in the drawings show environmental features of the tire and form no part of the following claim:
